(57) **CLAIM**

The ornamental design for a modular stick, as shown and described.

DESCRIPTION

FIG. 1 is a front perspective view of a modular stick showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an exploded view thereof; and,

FIG. 9 is a cross-sectional view of the modular stick, as indicated in FIG. 4.

The broken lines shown represent environment structure and form no part of the claimed design.
